UNITED STATES PATENT OFFICE.

EDWARD P. CALDWELL, OF CHICAGO, ILLINOIS.

DESIGN FOR A RAIL-JOINT CHAIR.

SPECIFICATION forming part of Design No. 26,742, dated March 9, 1897.

Application filed November 16, 1896. Serial No. 612,374. Term of patent 7 years.

To all whom it may concern:

Be it known that I, EDWARD P. CALDWELL, of Chicago, Cook county, State of Illinois, have invented a new and original Design for Rail-Joint Chairs, of which the following is a specification.

The leading feature of my design consists in the three parts of the chair of different thicknesses, two of said parts extending horizontally in opposite directions from the other and the third part being inclined and curved and extending above the other two parts.

In the accompanying drawings, forming part of this specification, Figure 1 is a perspective view of a rail-joint chair made in accordance with my new and original design, Fig. 2 is a cross-section of the finished chair.

In the drawings, A represents the outer horizontal part of the chair, and B the inner horizontal part of the same, the part B being of greater thickness than the part A. Extending above and formed integrally with these two parts is the part C, which is of

greater thickness than either of the parts A or B. The part C is bent down at c in angular form over the part B, so as to leave an angular recess between the upper surface of the part B and the lower surface of the portion c of the part C, and then the part C extends in a curved form upward at C' and has an inclined upper edge C''. Each of the parts A, B, and C is of uniform thickness throughout, and the upright curved portion C' of the part C is nearly over the edge of the part B. The part A is provided with the rectangular openings D, extending through it.

What I claim is—

The design for a rail-joint chair substantially as herein shown and described.

In testimony whereof I have hereunto set my hand this 26th day of October, A. D. 1896.

EDWARD P. CALDWELL.

In presence of—

R. E. LINDSTROM,
A. C. PAUL.
